Primary Examiner — Mary Ann Calabrese*Assistant Examiner* — Sloan Rozin(74) *Attorney, Agent, or Firm* — Tyler J. Sisk; Casimir Jones, S.C.(57) **CLAIM**

The ornamental design for a work table, as shown and described.

DESCRIPTION

FIG. 1 is a three-quarter perspective view showing our new design of a work table;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in FIGS. 1 through 7 are for the purpose of illustrating environment, and form no part of the claimed design.

1 Claim, 7 Drawing Sheets(56)
